UNITED STATES PATENT OFFICE

2,597,946

APPARATUS FOR THE TREATMENT OF
EXTERNAL SURFACES OF CANS

Albert M. Olson, Wauwatosa, Wis., assignor to
Chain Belt Company, Milwaukee, Wis., a cor-
poration of Wisconsin

Application December 20, 1946, Serial No. 717,498

9 Claims. (Cl. 15—70)

1

This invention relates to apparatus for the drying and treatment of cans and other containers being generally of circular cross section. In present canning practice cans are filled with comestibles, sealed and are heated so as to sterilize their contents. Next the cans are cooled in apparatus such as that disclosed in prior U. S. Patent No. 2,348,440 granted May 9, 1944. Subsequent to this operation the cans are labeled and packaged prior to shipment or storage.

In older and less advanced processes the cans are labeled and packaged immediately after sterilization or after they have been cooled down to about 120° F. Accordingly, there is no need for apparatus to remove the moisture from the cans, as it quickly evaporates under the influence of the very high temperatures. In the subsequent storage of these packaged cans it has been found that an elevated temperature of approximately 100° F. may be maintained for a month or more. This elevation of temperature is responsible for the breakdown of ascorbic acid (vitamin C) and further produces taste defects in the comestibles.

It has been found in the treatment of some comestibles, particularly the citrus products, that if the product be cooled immediately after sterilization, the food value, the vitamin content and the storage life without taste defect, is enhanced to a great degree. These methods have been applied with a great deal of success with the aforesaid mentioned apparatus. However, since the comestible will be cooled down to a temperature, which is substantially at 70° F., to insure the named benefits, a film of moisture is retained on the cans when they are removed from the cooling apparatus. For the moisture will not evaporate quickly after the cans are cooled down to the point which is most beneficial to the quality of the comestible.

The cans are generally cooled by means of rotation in a liquid bath, and a film of moisture is found adhering to the external surfaces of the cans when they are removed therefrom. This retards the labeling operation as the cans must be dry for the proper affixing of labels and is consequently a reason for increased cost and impeded productivity in the canning industry. Most of the label binders used in the canning industry today are lacquer-like and have a resinous base. These binders are not miscible with water. Therefore, it is apparent that all moisture must be off the external surfaces of the cans prior to labeling. Frequently it is found necessary to entirely disrupt the "straight line" methods of food processing in order to remove the external

2

moisture from the cans in order to render them ready for labeling. Further, attempts have been made to produce an apparatus to remove surface moisture, but these machines have been only partly effective in the past and in consequence have retarded production to a point where their use has been discarded.

Also it is a very important aspect of canned food merchandising to have an attractive container. During the aforesaid mentioned steps of sterilizing, cooling, and handling the cans are apt to become covered with lime deposits or other foreign material which mar their appearance and are not conducive to sales appeal. This invention overcomes these problems in an entirely facile manner, for:

It is the object of this invention to provide apparatus which will facilely remove moisture from the surfaces of the containers of circular cross section.

It is further the object of this invention to provide apparatus which may be readily integrated into canned food production lines to remove moisture from the surfaces of the containers.

Still another object of this invention is to provide an apparatus to continuously remove moisture from containers which are conveyed in a stream with longitudinal axes aligned.

Another object of this invention is to provide apparatus which will remove moisture from the surfaces of the containers of circular cross section without damage to said containers.

Still another object of this invention is to provide apparatus to remove moisture from the surfaces of cylindrical containers which may be adapted to function in said manner or which may be rendered inoperative without disrupting a canned food production line.

Another object of this invention is to produce a can free from surface moisture which is attractive in appearance.

Another object of this invention is to provide apparatus which will quickly remove foreign matter from the external surfaces of cans.

A further object of this invention is to provide an apparatus which will rapidly perform the above mentioned effects.

Other objects will appear in the reading of the following specification and in study of the divers views.

Referring to the figures of the accompanying drawings a preferred embodiment is illustrated. The same reference numerals designate like parts throughout the views.

Fig. 1 is a plan view of the improved apparatus partly broken away to show its internal arrangement.

Fig. 2 is a front elevation of the apparatus.

Fig. 3 is a sectional view of the apparatus taken along the line 3—3 of Fig. 2.

Fig. 4 is an end view of the apparatus in Fig. 2 at the line 4—4 of Fig. 2.

Fig. 5 is a perspective view, partly broken away, of the apparatus.

Referring to Fig. 1 it is apparent that the apparatus 10 is integrated into the conveyer system 11 of a canned food production line. The ease of this adaption is apparent as the incoming conveyer 12 and the outgoing conveyer 13 are placed adjacent the inlet and outlets respectively of the apparatus 10.

Referring to Fig. 2 it will be noted that the machine 10 is mounted on an incline relative to the frame 14 and is covered with a pleasing appearing housing 15 which has functional purpose which will be noted later on. As noted in Figs. 1 and 2 the brush 16 and the roller 17 are mounted with their longitudinal axes in parallel relationship. The roll 17 and the brush 16 are rotated in the instant embodiment at about 1200 R. P. M., energy being supplied by the motor 18 attached to the frame 14; this is connected by means of a conventional belting arrangement 29 to the roll and brush respectively. It will be noted that the rotation of the roller 17 is clockwise in Fig. 4 as is the rotation of the brush 16, and cans 21 thus rotate in a counterclockwise direction.

Placed between the brush 16 and the roller 17 is the supporting member 19. This member is shown in Fig. 3 as being a circular wooden element. However, divers other materials are suitable, and the shape may be either square or any other convenient shape. The supporting member 19 is attached to adjustable brackets 20 and 21 at each end of the machine. It will be noted that the longitudinal axis of the supporting member 19 is in angular relationship to the longitudinal axes of the brush 16 and the roll 17.

The distance between the driving roll 17 and the brush 16 can be varied. This is by reason of the adjustable mounting of the brush 16 and can be appreciated by reference to Figs. 1 and 4. The roll 17 is also adjustably mounted to the brackets 26 and 27 which are affixed to the frame 14. Said roll is covered with a pliable resilient material which may be rubber as in the instant embodiment. In the instant embodiment the machine is adjusted to accommodate a 404 x 700 or No. 3 tall can; this can is 4 1/4" in diameter by 7" long. The brush 16 is arranged so that the bristles of said brush are deflected at the point of contact shown at 28, when the apparatus is operating. Such an adjustment may be accomplished when the machine is not operating, by adjusting the roll and brush so that the bristles are substantially free of the surfaces of the can; then during the operation of the apparatus the high speed of rotation of said brush causes the bristles to radially extend and contact the cans as shown in Fig. 3. In the disclosed embodiment of the invention the roll 17 and the brush 16 are both rotated at approximately 1200 R. P. M. during normal operation. Thus it is apparent that the cans 21 entering the machine are moved forward through the machine in a helical manner. Also, the external surfaces of the can are swept free

of moisture and any other adhering material by the action of the brush 16. Since the cans 21 are also rotating in a counterclockwise direction at considerable speed, moisture is also centrifugally removed therefrom. The adjustable guards 24 and 25 are placed at each end of the brush and roll so as to prevent erratic movement of the cans as they engage said brush and roll; also a longitudinally extending guard rod 30 further serves the same purpose.

The moisture is removed from the brush by means of centrifugal action and the action of stripping elements, disposed about different portions of its periphery. The blade 22 (See Fig. 3) is disposed along the length of the brush at its lower portion in parallel relationship; as the bristles pass this element, the moisture is removed therefrom. Also disposed adjacent the upper portions of the brush the baffle and channel member 23 is arranged to collect moisture which is thrown from the brush and convey it away from said cans and to further remove moisture from said bristles. The shielding 15 about the entire apparatus prevents any splashing so that adjacent apparatus in a canning plant are not affected in any manner. The bottom of the apparatus is open so that water removed from the cans and brush may fall to the floor and be drawn off without further affecting the cans. As the cans 21 leave the conveyor 12, they are moved along at spaced relationship through the apparatus, thus there is no opportunity for the rapidly rotating cans to damage one another. Meanwhile centrifugal action occasioned by the rapid rate of rotation of said cans and the brushing action of the dry brush effectively remove the surface film of moisture from the cans; whereupon the cans are deposited on the outgoing conveyer 13 and are sped away dry and ready for immediate labeling. Further, because of the wiping action of the brush 16 the cans are cleansed and somewhat polished as they pass through the machine; this permits an attractive appearing can to be produced.

The helix angle between the can roll 17 and the supporting member 19 in this embodiment is 5°. Therefore, in considering the speed of rotation of said roll, it is apparent that this machine will effectively dry 125 cans of the aforesaid mentioned size per minute.

Another important element of this invention is that its function as a drier may be readily terminated should the food line be put to other processes which would not entail the drying of cans prior to labeling, i. e., if canned comestibles were to be heated and stored while hot. This would be accomplished simply by moving the brush 16 away from the dry roll 17 whereupon the machine functions as part of the conveyer 11. This feature enables economical canning plant operation.

The helix angle between the supporting member 19 and the roll 17 has been found to be at the optimum of 5° in the embodiment herein described. However, in adjusting the machine for divers size cans this angle may be substantially varied within the range of 2° to 10° to secure optimum operating conditions. The driving roll 17 in the instant embodiment is 3 1/4" in diameter, and the cleaning brush 16 is approximately 10" in diameter; these elements may be varied to conform to individual conditions and operation. The brush as herein shown has wire drawn bristles of the "Tampico" variety, although equivalent material such as "nylon," etc. may be used.

In operation it has been discovered that the machine operates best when the incoming canned comestibles are at a temperature near the dew point of water; generally 70° F. is satisfactory. Also the brush 16 and the roll 17 are best arranged when their longitudinal axes are about 15° from the horizontal. This permits the angular arrangement of the entire machine and allows for the ready withdrawal of water, an example of which is the disposition of the baffle and channel member 23 and the stripping element 22.

In the foregoing manner the cans pass through the machine at a very rapid rate, are cleansed and dried and ready for the next step of labeling.

Further, another use which is extremely beneficial to the food canning industry is apparent when it is considered that some comestibles are introduced into cans when they are hot (on the order of 200° F.). Before the capping and sealing of these cans a portion of the comestible overflows and dries very quickly on the peripheral portion of the cans. The dry comestible can be removed only with great difficulty, if at all, in modern canning practice. Thus the aforesaid mentioned sterilizing apparatus may become polluted with the comestible with apparent results. If the above disclosed apparatus be integrated between the sealing and sterilizing apparatus, the comestible is readily removed when water or some other suitable solvent is sprayed from a nozzle 31 onto the containers, as shown in Fig. 5.

This invention is not limited to the embodiment described and illustrated; as variations of it will occur to those skilled in the art; hence, it is to be limited only by the clear import of the following claims.

I claim:

1. An apparatus for treating containers of circular cross section comprising, conveyer means arranged to deliver said containers with their longitudinal axes aligned, a rod-like member for supporting said containers, said member being disposed parallel to the direction of travel of said containers, adjacent rotating brushing means arranged in angular relationship to said supporting means, an adjacent roller member arranged parallel to said brushing means so that containers moving between said brushing means and said roller member have changing portions of their peripheries contacted by said brushing means whereby said containers are rapidly advanced and rotated between the roller and brushing means while peripheral surface moisture and foreign material is swept free of said containers, means to rotate said brushing means and said roller member, and conveying means to remove said containers.

2. An apparatus for removing moisture from the external surfaces of cans comprising, conveyer means arranged to deliver said containers with their longitudinal axes aligned, a supporting member for said containers disposed parallel to the direction of travel of said cans, adjacent rotary brushing means arranged in angular relationship to said supporting member, an adjacent rotating drive member arranged parallel to said brushing means at a point removed therefrom so that containers moving between said brushing means and said drive member have all portions of their peripheries grazed by said brushing means whereby surface moisture is removed, means to rotate said brushing means and said drive member, stripping means contacting said brushing member extending the length of said

member to remove moisture from said brushing member, and conveying means to remove said containers.

3. Apparatus according to claim 2 in which the axis of the rotatable brushing means and the axis of the rotating drive member are arranged substantially at an angle of 5° with said supporting member.

4. An apparatus for treating containers of circular cross section comprising, conveyer means arranged to deliver said containers with their longitudinal axes aligned, a supporting member for said containers, adjacent rotatable brushing means arranged in angular relationship to said supporting means, an adjacent rotatable drive member arranged parallel to said brushing means so that containers moving between said brushing means and said drive member have changing portions of their peripheries contacted by said brushing means and said rotatable means whereby said containers are forwardly advanced and rapidly rotated while peripheral surface moisture and foreign material is swept free of said containers, means to rotate said brushing means and said drive member, a parallel troughed baffle member arranged immediately contiguous said brushing means whereby matter impelled from said brushing means is conducted away from said containers, and conveying means to remove said containers.

5. An apparatus for removing moisture from the external surfaces of cans comprising, conveyer means arranged to deliver a series of cans having their longitudinal axes aligned, a supporting member for said cans, adjacent rotatable brushing means arranged in angular relationship to said supporting member, an adjacent rotatable drive member arranged parallel to said brushing means so that cans moving between said brushing means and said drive member have all portions of their peripheries grazed by said brushing means whereby surface moisture is removed while the cans are impelled through said apparatus, means to rotate said brushing means and said drive member, stripping means contacting said brushing member extending the length of said member to remove moisture from said brushing member, a housing substantially open on three sides covering said contacting elements whereby moisture removed from said cans is restrained from again contacting said cans, and conveying means to remove said containers.

6. Apparatus for treating containers of circular cross section comprising, conveyer means arranged to deliver said containers with their longitudinal axes aligned, supporting means for said containers disposed in the path of travel of said containers, adjacent rotatable brushing means arranged in angular relationship to said supporting means, an adjacent rotatable drive member arranged parallel to said brushing means so that containers may move between said brushing means and said drive member while said containers are advanced through said apparatus and rapidly rotated, the peripheral foreign material meanwhile being swept free of said containers, means to rotate said brushing means and said drive member, guard means disposed adjacent said containers whereby erratic movement of said containers is restrained, and conveying means to remove said containers.

7. An apparatus for removing moisture from the external surfaces of cans comprising a support for said cans, means adjacent said support for rotating said cans, brushing means substan-

tially twice the diameter of said cans contiguous said supporting means arranged parallel to said can rotating means whereby cans may pass therebetween, means for rotating said can rotating means and brushing means in the same direction at substantially 1200 revolutions per minute, said support being angularly disposed with respect to said brushing means so that containers will be helically advanced by the action of said brushing means and said can rotating means on the cans as foreign matter is removed from their surfaces.

8. In apparatus for removing foreign matter from the external surfaces of cylindrical containers, the combination of a stationary support engageable by a lower portion of the peripheral wall of the containers when lying on their sides; a container-rotating roll engageable by said peripheral container wall, said roll being laterally displaced from and disposed substantially higher than said support; a rotatable brush disposed in laterally spaced relation to said roll to provide a container-receiving space therebetween above said support, the lines of contact of the roll and brush with said container wall being substantially diametrically opposed; and means for rotating 25 said roll and brush whereby the roll induces ro-

tation of the containers and the brush removes the foreign matter from the container surfaces.

9. Apparatus according to claim 8, including a stripping element engaging the periphery of the brush for removing therefrom matter which has been transferred to the brush from the containers.

ALBERT M. OLSON.
